INVENTOR

George F. Voight

UNITED STATES PATENT OFFICE.

GEORGE F. VOIGHT, OF OAKLAND, CALIFORNIA.

WIRE FASTENER.

Application filed March 9, 1925. Serial No. 14,175.

To all whom it may concern:

Be it known that I, GEORGE F. VOIGHT, a citizen of the United States, residing at Oakland, in the county of Alameda and State of California, have invented new and useful Improvements in Wire Fasteners, of which the following is a specification.

My invention relates to improvements in wire fasteners particularly adapted for attaching wire lath to the wall sheathing of stucco structures, although also useful for other purposes, and in which a metal furring element is slidably carried on the forward end of a driven element.

One of the objects of the present invention is the provision of a furring element in the form of an arch, in which the side frame is adapted to seat against the wall sheathing, and the crown or apex is adapted to support the lath.

A further object is the provision of an outwardly projecting flange along both edges of the arch, for reinforcing it and to prevent collapsing thereof when the fastening element is accidentally driven excessively in securing it to the wall sheathing.

A still further object is the provision of a hub or its equivalent at the margin of the apex opening, adapted to engage the sides of the fastening element for holding it in axial alignment with the furring element.

With the foregoing and still further objects and purposes in view which will appear as the description proceeds, my invention resides in the combination and arrangement of parts and in the details of construction hereinafter described and claimed, it being understood that changes in the precise embodiment of the invention can be made within the scope of what is claimed without departing from the spirit of the invention.

In the accompanying drawings—

Figure 1 is a side elevation of a wire fastener constructed in accordance with my invention, seated against the face of a section of wall sheathing preparatory to attaching it thereto, and a portion of wire lath in engagement with the fastener;

Figure 2 is an end view of the fastener secured to the wall sheathing, a section of the wire lath secured between the head of the fastening element and the upper end of the furring element, and a section of stucco composition in the immediate background.

Figure 3 is a view in vertical cross section of the furring element, a cross section of a portion of the lath, a sectional view of a portion of the wall sheathing, and the fastening element in elevation projecting through the furring element and a distance into the wall sheathing;

Figure 4 is a median, vertical sectional view, longitudinally through the furring element;

Figure 5 is a top plan view of the device; Figure 6 is a bottom plan view thereof; and

Figure 7 is a view on line 7'-7', Fig. 1. Referring to the drawings in detail, throughout which like reference characters designate like parts:

The numeral 1 designates the wall sheathing, which is preferably nailed in close-jointed order across the studding of the exterior walls of the structure, and which forms the backing of the stucco composition. If so desired, the wall sheathing may be provided with a surfacing of building paper, and the term "wall sheathing" or "sheathing", where the same occurs throughout the description and the claims, shall mean to include the building paper.

2 designates my improved wire fastener, which embodies a fastening element 4 co-operable with a furring element 5.

The fastening element comprises preferably a nail having the usual shank member 6 and head 7.

The furring element 5 comprises a strip 90 of flat metal, which has its ends bent downwardly, with an outwardly incline, thereby forming an intermediate or body portion 8 provided at each end with a supporting leg 9. Both side edges of said body portion, and 95 also of said legs 9, are struck upwardly at an angle to form opposed marginal flanges 10 extending from the free end of one of said legs across said body portion to the free end of the opposite leg.

The furring element is in the form of an arch, of which the body portion 8 forms the apex, and the legs 9 the end supports, and the flanges 10 are provided, primarily, for the purpose of providing a certain degree of 105 rigidity to the comparatively thin metal of which the furring element is formed, and to prevent crushing thereof in case the fastening element 4 is accidentally driven excessively in attaching the device to the wall 110

sheathing. Intermediate portions of said flange also function for another purpose, which will be hereinafter fully described.

The body portion 8 is provided with a central, vertically extending, opening 11, around the margin of which, on the lower side of said body portion, is a hub or sleeve 12, through which opening and sleeve projects the shank 6 of the fastening element 4.

10 The shank 6 is intended to fit sufficiently tight in said opening 11 and sleeve 12, to be normally frictionally bound against the sides thereof against normal longitudinal movement relative to the said furring element, but 15 slideable through said opening and sleeve when the furring element is caused to seat against the wall sheathing and the fastening element operatively driven thereinto.

The hub or sleeve 12 is adapted both to 20 engage and frictionally hold the shank 6 against normal longitudinal movement relative to the furring element, and to engage and hold said shank in substantial axial 25 alignment with said furring element and to normally prevent tilting or "racking" thereof relative to the latter when the device is operatively manipulated for stretching and attaching the wire lath.

13 designates a fragmental portion of the 30 wire lath, which may comprise such wire cloth as is commonly known as "poultry netting", or it may comprise any other suitable metal mesh fabric.

The furring element 5 is intended to be 35 engaged with the wire lath 13, between an upper portion of one of the flanges 10 and the shank 6, and to hold the lath a distance outwardly from the wall sheathing 1, and the fastening element 4 is adapted to be 40 driven into the latter until the head 7 engages the lath and binds it down firmly and permanently against the body portion 8.

As hereinabove set forth, the flanges 10 are intended, primarily, as means for providing rigidity to the comparatively thin sheet metal of which the furring element is 45 constructed, however, the intermediate or upper portions of the flanges also function for engaging the wire lath 13 and to hold it 50 against the shank 6 and prevent it from slipping off from the body portion 8.

The furring element is intended to be 55 "factory-built" onto the forward end of the shank, and to apply the device it is simply necessary to project the forward end of the shank 6 including the furring element, 60 through the proper meshes of the wire lath to be attached, hook one of the flanges 10 underneath one of the lath wires and then drive the fastening element into the wall sheathing until the head 7 engages the lath wire and binds it against the body portion 8 and the furring element against the wall 65 sheathing.

14 designates the stucco composition,

which is applied by spreading it on the wall sheathing and on and around on the wire lath until a suitable thickness is obtained.

The wire fasteners may be disposed at intervals along the lath as found best suited 70 for the work to be performed. I have found in practice that by spacing them about eight inches "center-to-center" each way an entirely satisfactory job may be obtained.

I claim:

1. In a wire fastener of the character described, a furring element formed of a strip of flat metal and having its ends bent downwardly, thereby forming an intermediate body portion having at each end a downwardly projecting supporting leg, an upwardly struck marginal flange on each side of said legs and body portion, said body portion provided with an opening, and a fastening element projecting through said opening and between said legs.

2. A wire fastener comprising, a furring element formed of an oblong strip of flat metal, opposite ends thereof bent downwardly, thereby forming a body portion having at each end a downwardly projecting leg, said legs and said body portion having their side edges bent to one side to form marginal flanges, said body portion having a central opening, means on the lower side of said body portion on opposite sides of said opening, and a fastening element projecting through said opening and between said means, said means adapted to engage said fastening element on opposite sides for holding it substantially in axial alignment with said wire fastener.

3. In a device of the character described, a furring element formed of a strip of flat metal, each end of which struck downwardly, thereby forming an intermediate body portion having a supporting leg at each end, said legs and said body portion being concavo-convex in cross section, a nail projecting vertically through said body portion, said nail having a head at its upper end, and a lath wire confined between said head and said body portion.

4. In a wire fastener of the character described, a furring element formed of a strip of flat metal bent flat-ways intermediate its ends, thereby forming an intermediate body portion having a pair of opposed supporting legs diverging towards their free ends, one of the side edges of said body portion being bent upwardly thereby forming a lath retaining flange, a nail projecting through said body portion and between said legs, said nail having a head at its upper end, and a lath wire confined between said head and said body portion intermediate said flange and the nail, said flange extending parallel with the plane of said legs and said nail.

5. In a wire fastener of the character de-

- scribed, a furring element formed of an oblong strip of flat metal having parallel side edges, bent intermediate its ends, thereby forming an intermediate body portion having at each end a downwardly projecting leg, said legs diverging towards their free ends, one of the side edges of said body portion having an upwardly projecting flange, said flange extending a distance along one of the side edges of each of said legs and a nail projecting vertically through said body portion, said nail having a head adapted to engage and bind a lath wire on said body portion intermediate said flange and said nail, said flange extending longitudinally of said strip of metal.
6. A wire fastener comprising, a furring element formed of a strip of flat metal bent flat-wise intermediate its ends, thereby forming an intermediate body portion having at each end a depending leg, a flange extending along each of the side edges of said legs, said flange continuing and ex-
- tending across the side edges of said body portion, and a cooperating driven element 25 projecting vertically through said body portion intermediate said flanges, said body portion adapted to receive and support a lath wire between one of said flanges and said driven element. 30
7. A wire fastener comprising, a spacing element formed of a strip of sheet metal bent upwardly intermediate its ends in the form of an arch, and a cooperating nail projecting vertically through the crown of said arch, the side edges of said strip at said crown being bent upwardly to form lath retaining means on opposite sides of said nail, said nail having a head adapted to operatively engage and bind a lath wire on said 40 crown between one of said lath retaining means and said nail.

In testimony of the foregoing being my own, I have hereunto affixed my signature this 2nd day of March, 1925.

GEORGE F. VOIGHT.
